UNITED STATES PATENT OFFICE.

JOHN H. ARCH, OF JACKSON, GREENE COUNTY, IOWA.

MOTOR.

SPECIFICATION forming part of Letters Patent No. 403,317, dated May 14, 1889.

Application filed November 28, 1888. Serial No. 292,087. (No model.)

To all whom it may concern:

Be it known that I, JOHN H. ARCH, a citizen of the United States, residing at Jackson township, (post-office address Scranton,) in the county of Greene and State of Iowa, have invented certain new and useful Improvements in Motors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to motors that are run by springs, and which are designed to run light machinery, such as scroll-saws, lathes, grinding-stones, sewing-machines, &c. The motor is controlled by a pendulum and escapement-wheel, and the shaft from which the power is taken is adjustable to adapt the motor to machines of different heights.

20 The improvement consists of the details of construction, which hereinafter will be more fully described and claimed, and which are shown in the annexed drawings, in which—

25 Figure 1 is a front view, parts being broken away, of a motor embodying my invention; Fig. 2, a top plan view; Fig. 3, a detail view showing the manner of adjusting the shaft from which the power is taken, and Fig. 4 a detail perspective view of a modification.

30 The sides A and B, which form the supports for the train of gearing, are held together by the brace-bars a. The winding-arbor B' is provided with the gear-wheel C and with the drum D, on which the spring E is wound, the lower ends of the spring being carried down and secured to the post e. The inner end of 35 the drum has the ratchet-teeth d, which are engaged by the pawl c in engagement with the said teeth. The gear-wheel C meshes with the pinion f on the shaft F, and the gear-wheel g on the shaft F meshes with the pinion h on 40 the shaft H. The gear-wheel i on the shaft H is in mesh with the pinion j on the adjustable shaft J. The curved bars K, held to the sides A and B and concentric with the shaft H, have a series of openings, k, in their length, 45 through corresponding pairs of which open-

ings the thumb-screws L pass and screw into threaded openings j' in the ends of the shaft J. By removing the thumb-screws L the shaft J can be raised or lowered to adapt the motor to machines of varying heights. When the 55 shaft is adjusted, the thumb-screws are replaced and form journals for the said shaft.

The speed of the motor is controlled by the scape-wheel m on the shaft M, the pallet-lever N, and the pendulum n. The shaft M is in 60 gear with the wheel g through the pinion o, mounted thereon. The power is taken from the adjustable shaft J by any well-known means, as the belt P, which passes over the band-pulley Q on the shaft f. 65

In Fig. 4 the shaft is extended at one end and passes through one of the curved bars, and the other end is held by a set-screw. The extended end is provided with an angular opening or is otherwise constructed to receive 70 a tumbling-shaft. In case a belt be the means for conveying the power any slack may be taken up in the same by adjusting the said driving-shaft.

Having thus described my invention, what 75 I claim, and desire to secure by Letters Patent, is—

1. In a motor, the combination of the curved bars having openings, the adjustable shaft J, having threaded openings in its ends, and the 80 thumb-screws, substantially as and for the purpose described.

2. The herein described and shown motor, composed of the sides A and B, the shaft B', having the gear-wheel C, the drum D, and the 85 ratchet-and-pawl connection between the drum and the gear-wheel C, the shaft H, having the pinion h and the gear-wheel i, the shaft J, having a pinion and threaded openings in the shaft ends, the curved bars K, having a series of openings, the thumb-screws L, and the escapement, combined, arranged, and operating substantially as and for the purpose described. 90

In testimony whereof I affix my signature in 95 presence of two witnesses.

JOHN H. ARCH.
